UNITED STATES PATENT OFFICE.

BENJAMIN DAY CHAMBERLIN, OF CORNING, NEW YORK, ASSIGNOR TO EMPIRE
MACHINE COMPANY, OF PORTLAND, MAINE, A CORPORATION OF MAINE.

MACHINE FOR THE MANUFACTURE OF BLOWN-GLASS ARTICLES.

1,124,701.

Specification of Letters Patent. Patented Jan. 12, 1915.

Application filed March 30, 1912. Serial No. 687,467.

To all whom it may concern:

Be it known that I, BENJAMIN D. CHAMBERLIN, a citizen of the United States of America, and a resident of Corning, New York, have invented certain new and useful Improvements in Machines for the Manufacture of Blown-Glass Articles, of which the following is a specification.

In my prior application filed February 7, 1911, Serial Number 607,179, I have shown, described and claimed mechanism for delivering to a preshaped blank, prior to the elongation thereof, a definite volume of blow-out air under a definite pressure and of means for holding for a definite time the pressure so created therein, in connection with means for subsequently admitting blowing air for the purpose of swelling the elongated blank within the mold. In the construction there shown the source of air for molding the blank is independent and distinct from the mechanism for creating the blow-out pressure, but the last named mechanism is in the connection between the source of molding air and the blow-pipe.

The invention here disclosed and claimed relates to improvements in the construction of the device of my said prior application whereby a plurality of injections of air may be made into the blank prior to the admission of molding air, this necessitating certain changes in the construction of the apparatus of my prior application, as will be hereinafter described and claimed.

Referring to the accompanying drawings in which corresponding parts are referred to by corresponding marks of reference: Figure 1 is a front elevation illustrating a general type of machine to which my invention is adapted. Fig. 2 is a fragmental front elevation of the blow-pipe frame, swinging mechanism therefor, and blow-out air mechanism, part of the blow-pipe frame being broken away for the purpose of illustration, the blow-pipe frame being in normal position. Fig. 3 is a fragmental side elevation of the mounting of the blow-pipe frame and the actuating mechanism therefor, the frame being shown in vertical or blowing position. Fig. 4 is a vertical section thereof with the blow-pipe frame horizontal. Fig. 5 is an enlarged fragmental front elevation, showing the blow-head and actuating mechanism therefor carried by the blow-pipe frame. Fig. 6 is an end view of Fig. 5. Fig. 7 is a

plan view of air head of Fig. 5. Fig. 8 is a longitudinal section through the blow-pipe chuck and blow-out air mechanism, together forming part of the air head.

For the purpose of describing the invention forming the subject matter of this application, I have shown diagrammatically in Fig. 1 a type of machine for use in connection with which my invention is applicable, although it should be understood that it is not restricted to this type of machine. As there shown such machine comprises a frame 1, having mounted in the bearing 2 in the upper part thereof, a tubular trunnion 3, forming part of the blow-pipe frame 4. Mounted upon the exterior of such bearing is a disk 5 having peripheral teeth 6, by which it is driven from a pinion 7. The pinion 7 is intermittently driven from a suitable source of power, in such manner that the disk 5 will, when the parts are in normal position, be rotated through a part of a revolution and will then be arrested and will then after a period of rest be driven through the remaining part of its revolution to return it to normal position. I do not deem it necessary to describe mechanism for accomplishing this intermittent drive of the disk as a device therefor is shown in my prior application, Serial Number 602,532, filed January 13, 1911.

At the base of the machine is located a molding mechanism comprising separable molds 88^a and means for dipping the same. The opening and closing and dipping thereof is accomplished through cam runs 8 and 9 respectively upon the rear face of the disk 5. It is not necessary to describe in detail the mechanism by which this may be effected as the same are shown in my said prior application.

For the purpose of causing the rotation of the disk to oscillate the blow-pipe frame around the pivot formed by its trunnion and to arrest its movement at certain desired positions during the rotation of the disk, the machine to which my invention is herein shown as applied includes a pair of toggle lever 10 and 11, connected together by the pin 12. The outer end of the link 10 is pivoted at 13 to arm 14 projecting radially from a collar 15 fixedly mounted on the bearing 2, in front of the disk 5. The outer end of the link 11 is pivoted to a stud 16 on the rear face of the blow-pipe frame 4. The

Link 10 carries intermediate of its length and on its rear face a roller 17 contained within a cam run 18 on the front face of the disk 5. As a result of this construction it 5 will be seen that as the cam run 18 is by the rotation of the disk 5 driven in the direction of the arrow in Fig. 2 and moved relatively to the fixed pivot 13 of the toggle lever system, the link 10 will be caused 10 to assume different angular positions around the pivot 13, and will thereby impart motion to the lever 11, connected to the blow-pipe frame, whereby the latter will be swung around the axis of the bearing 2. The cam 15 run 18 is so shaped that with the parts in normal position the blow-pipe frame is substantially horizontal, and that it will during the first movement of the disk be swung in a direction reverse of that of the movement 20 of the disk and will then be reversed in its movement and swing in the direction of the disk until vertical, (which position it will occupy on the stopping of the disk) and will upon the subsequent movement of 25 the disk to complete its rotation be temporarily held in its vertical position, and will then, by a movement reverse to that of the rotation of the disk, be swung into its normal horizontal position. The time in which 30 the blow-pipe frame is held vertically during the rest of the disk 5 is to give time for the elongation of the glass on the blow-pipe, while the time it is vertical during the rotation of the disk corresponds to the 35 period in which the glass is blown in the mold.

Mounted on the main frame to one side thereof, is a glass shaping mechanism, preferably of the construction shown in my 40 other application filed February 1, 1912, Serial Number 674,814, and which comprising marvering surfaces 19, and a gage mold 92, the latter of which is adapted to be momentarily projected on the glass on the blow-pipe iron to shape the same, the position of 45 such shaping devices being such that the blow-pipe comes into cooperative relation therewith during the first tilting movement of the blow-pipe frame.

50 The blow-pipe frame comprises a hollow casting 20, with which the trunnion 3 is integral, having projecting from one end thereof pipes 21, 22, which on their outer end carrying the air head 23, the opposite end of the blow-pipe frame being provided 55 with a blow-pipe rest 24, in which the blow-pipe may rotate.

The blow-head comprises a casting 25, carried by the outer ends of the pipes 21, 22 in which is contained a cylinder 26, having at its inner end a ball bearing 27, by which is carried the shell 28 of a chuck. Pivoted within the chuck shell to move radially therein are jaws 29, the outer ends of 65 which are normally thrown apart by springs

30 contained within the shell 28. Slidably mounted in the inner end of the chuck shell is a collar 31, which when projected within the shell will cause the forward ends of the jaws 29 to close upon a serrated shoulder on the end of the blow-pipe 89, if the latter be located therein. In my prior application, Serial Number 602,432, hereinbefore referred to, I have shown this construction of chuck jaws as well as mechanism for 70 sliding the collar 31 within the shell for the purpose specified. The chuck shell carries peripheral teeth 34 which mesh with a pinion 35 on a shaft 36. The outer end of this shaft has a bearing in the blow-head casting 25 and carries near on its inner end a beveled pinion 37, meshing with a corresponding pinion 38 upon the forward end of a shaft 39, projecting forwardly through the hollow trunnion 3 and driven in any approved manner. 75

The rear end of the chuck shell 28 has screwed therein a rearwardly projecting nipple 40. A packing 41 is located in front of such nipple and against it the blow-pipe is seated by the pressure of the jaws 29. Around the rear end of the nipple is a cup washer 42 which serves as an air tight joint between such revolving nipple and the stationary cylinder 26. 80

Located on the air head casting 25 is a molding air valve 43, which controls the admission of molding air from the central cavity of the blow-pipe frame to the interior of the cylinder 26, the inlet port in the latter 100 for such molding air being shown at 44. The connection between the air valve and central cavity of the blow-pipe frame is formed by the pipe 21, while the central cavity is itself in communication with a 105 source of air under pressure by means of a flexible pipe 45. The air valve 43 is actuated to admit molding air into the cylinder 26 at the proper time to swell the glass to its finished form by means of a rod actuated at the proper time by a cam 90 on the rotating disk 5. 110

Having thus described the general nature of a machine to which my invention may be applied, I will now describe in detail those 115 parts of the machine which are more closely allied with the invention here sought to be protected.

Mounted on the head of the main frame and in the same plane as the disk 5 is the 120 stationary cam plate 47, which, as shown, is a sector concentric with the main bearing 2, carrying a series of radially adjustable cams 48, 49, 50, 51 and 52 and a series of angularly adjustable trip projections 53, 54, 55 and 56, the rise of the first named series of cams being radial in respect to the axis of oscillation of the blow-pipe frame while the rises of the projections 53 to 56 inclusive are at right angles thereto. 125

5 Mounted in the outer head of the cylinder 26 is the piston rod 57, the inner end of which is reduced in diameter and carries an enlarged head 58 having a packing 59 thereon which is normally seated against the rear end of the nipple 40 by the spiral spring 60 upon the piston rod 57. Slidably mounted upon the reduced portion of the piston rod 57 is the piston head 61, having ports 62 therethrough, while fixedly mounted upon the piston rod upon the outer side of the piston head is the washer 63, having a suitable packing 91 on its inner face, and adapted when in contact with the piston head to seal 10 the ports therein. The piston rod has upon its outer end and upon the outside of the cylinder 26 a head 64, provided with a notch 65 in which a laterally extending finger 66 on the outer end of a rod 67 mounted in the 15 blow-head casting 25 and in bearings on the body of the blow-pipe frame is adapted to engage. The inner end of this rod is provided with a foot block carrying a bearing roller 68, adapted to contact with and be 20 lifted by the cams 48, 49, 50, 51 and 52 and is also provided with a laterally extending arm 69 having on the end thereof a roller 70 adapted to contact with the projections 53, 25 54, 55, and 56 on the fixed cam plate where- 30 by the rod will be given an angular motion. The rod has thus two motions, in its bearings, the one longitudinal, which when the finger 66 thereon is in engagement with the notch 65 in the block 64 on the piston rod 57, 35 retracts the latter, and the other an angular or rotary movement which disengages such finger from the piston rod and permits the spring 60 to project the latter. The rod 67 is normally projected inwardly by the spring 40 71 and given such angular position as will cause its finger 66 to normally engage the notch 65, by a spring 92 fast to the blow-pipe frame and bearing on the arm 69, and the head 64 terminates in a beveled face 72, upon 45 which the finger 66 will bear and down which it will slide when the rod 67 is subsequently allowed to drop by the cams 48 to 52.

Pivoted to the upper end of the cam plate 50 is a tappet 73, the upper end of which has a beveled face 74 corresponding generally to the fixed projections 53 to 56 inclusive upon the cam plate and the lower end of which projects forwardly in the form of a foot 75, the tappet being provided with a heel 76 bearing upon a cam 77 upon the disk 5, by which the tappet will be lifted, this occurring about the time the mold is closed by the 55 rotation of the disk.

60 Guided in bearings in the air head casting
25 and on the body of the blow-pipe frame is
the rod 78 normally projected inwardly by a
spring 79, the outer end of the rod having
thereon two striker pins 80 coacting with a
65 three armed lever 81 pivoted to the air head

casting 25. An aperture 82 is formed in the wall of the cylinder 26 and this aperture is adapted to be closed by a disk 83 carried on one arm of the lever 81 and pressed to its seat by the spring 84. Another arm of this lever 81 carries a pin 85 thereon which engages in one arm of a bell crank lever 86 also mounted on the blow head casting 25, the other arm of such lever being adapted at times to coact with a pin 87 on the head 64 of the piston 57, to slightly raise the latter, this being contemporaneous with the closing of the aperture 82 by the disk 83.

It will be noted that the cams 48 and 49 which are situated respectively above and below the horizontal diameter drawn through the central pivot 2 are reversed and have interposed between them the bridging piece 88 and that the remaining cams 50, 51 and 52 correspond in their facing to the cam 49

With the mechanism hereinbefore described and with the parts thereof in the normal position as shown in Fig. 1, the 90 operation is as follows:—A blow-pipe with a gather of glass thereon is inserted in the chuck on the blow-pipe frame and the guide thereon, and motion is imparted to the pinion 7 whereby the disk 5 will be set in rotation in the direction of the arrow, Fig. 2. This results in a reverse movement of the blow-pipe frame, whereby the gathering end of the iron is raised past the shaping 95 devices and the blow-head is lowered. During this reverse motion of the blow-pipe frame, the cam 48 shoves the rod 67 outwardly, and as the finger 66 thereon is in engagement with the notch 65 on the piston 57, the latter is retracted. At about the 100

time the blow-pipe frame reaches its limit of movement in the direction specified, the trip projection 53 partially rotates the rod 67 and disengages the finger thereon from the notch in the piston and permits the 110 spring 60 to project the latter inwardly. The retraction of the piston by the cam 48 unseated the head 58 from the nipple 40 of the blow-pipe chuck, and not only causes such relative movement of the piston head 115 61 on the piston rod as uncovered the ports 62 but retracted the piston head 61. The projection of the piston 67 first closes such ports 62 and then drives the piston head 61, thus forcing a definite quantity of air into 120 the preformed gather on the blow-pipe to form a central cavity therein and to clear the bore of the blow-pipe from any glass that may have been forced therein by the action of the gage mold. The projection 125 of the piston also seats the head 58 on the nipple 40 and seals the end of the blow-pipe, trapping the air therein. Upon the direction of rotation of the blow-pipe frame being reversed the roller 68 upon the rod 130

67, will run down the cam 48 and the finger 66 will contact with the beveled face 72, on the head 64 of the piston and be given such angular movement as will permit it to snap 5 again into the notch 65. Upon the continued movement of the blow-pipe frame to swing it to vertical position with the air head up, the rod 67 will be successively lifted by the fixed cams 49, 50 and 51, re- 10 tracting the piston 57, and will be successively released from the piston by the trip projections 54, 55, and 56 respectively. The number and position of the several fixed cams 49, 50 and 51 and corresponding trip 15 projections 54, 55 and 56 may be varied at will to obtain the desired results but I have found it advisable to employ in addition to the cam 48 which produces the initial cavity in the blank, three cams 49, 50 and 20 51, to produce successive blowing out of the blank prior to the elongation. I have also found it desirable to make the several cams adjustable on the fixed cam plate whereby the distance through which the piston head 25 is retracted the several times may be varied, thus affording means to control the quantity of air forced into the blank at each stroke of the piston.

Prior to the blow-pipe assuming its vertical position the rod 67 is shoved outwardly 30 by the fixed cam 52, and the blow-pipe frame comes to rest in a vertical position with the rod 67 on the cam 52. The rotation of the disk 5 is now arrested to permit 35 the elongation of the blank, and after a proper time therefor, it is again put in rotation, the blow-pipe frame remaining stationary. The renewed rotation of the disk 5 lifts through the cam 77, the tappet 73, 40 the upper beveled face 74 of which contacts with the roller 70 to rotate the rod 67 to release the piston 57, whereby air will be forced within the elongated blank to swell the same within the mold. The continued 45 rotation of the disk will further raise the tappet 73, whereby the foot 75, will by contacting with the rod 78, lift the latter, and will shift the three arm lever 81 to close the aperture 82 in the cylinder and to slightly 50 withdraw the piston 57 to unseal the head 58 from the nipple 40, and uncover the ports 62 in the piston 61. The molding air valve 43 is now actuated by the rotation of the disk and the gather is fully blown thereby, 55 after which the continued rotation of the disk closes the said valve and restores the blow-pipe frame to normal position.

It will be noted that the cylinder 26 is in communication with the outer atmosphere 60 through the aperture 82 during the periods in which the admission of air into the blow-pipe is due to the action of the piston pump, and that the means for closing such aper-

ture and simultaneously unseating the head 65 58 from the nipple 40 effect an uninterrupted 65 communication between the molding air valve and the blow-pipe.

It should be further noted that when the parts are in their normal position the rod 67 is retracted slightly, whereby the end of the nipple 40, and the ports 62 will be opened, so that when the blow-pipe is placed in the blow-pipe frame, with its end in the chuck, the interior of such blow-pipe will be in communication with the external air 75 through the blow-out mechanism, thus precluding any premature compression of air within the blow-pipe during the closing of the chuck thereon.

It will be further noted that prior to the introduction of each air change the interior of the blow-pipe is placed in communication with the external air through the nipple 40, and ports 62, which are opened on the rearward movement of the plunger preparatory 85 to the forcing in of the next change, and through the aperture 82.

I desire to call attention to the necessity, especially in the manufacture of light and delicate articles, such as bulbs for incandescent electric lights, of introducing a limited and definite quantity of air into the preformed blank and positively holding in the gather for a short period the pressure so created. The amount of air introduced 95 into the blow-pipe at this time is relatively small, and a small leakage therefore has the effect of greatly reducing the predetermined pressure in the blank, with a variation in the amount the blank is "blown out," which 100 acts to destroy uniformity in the subsequent molding. Hence it is important that the sealing of the blow-pipe be as perfect as possible, and the ability to accomplish this is aided by placing the source from which 105 the blow-out air is derived, and the valve by which it is controlled, both as close to the blow-pipe as possible, as the number of possibly leaky joints is thus reduced.

It will be noted that in the construction 110 shown the source and valve for the blow-out air are both on the blow-pipe frame and immediately adjacent to the end of the blow-pipe. Moreover since the valve for releasing the blow-out pressure is in the connection 115 between the source of molding air and the blow-pipe, its use does not provide any additional point at which the molding air may escape, while the use of a piston pump, such as shown, for delivery directly to the 120 blow-pipe on each stroke the exact quantity of air necessary for the blow-out, provides for the precise regulation of the air pressure for that purpose.

It will be further noted that the blow-out 125 air introduced into the blank is entirely

separate and distinct from any air that may be subsequently introduced into the blank to give it the shape of the finished article.

Inasmuch as the claims of this application are directed solely to the air mechanisms, I do not by failure to make claims herein directed to other inventive features shown herein, abandon the same. Claims covering certain of such other features are 10 reserved for my other applications Serial Number 491,812, filed April 23, 1909, Serial Number 551,198 filed March 23, 1910, and Serial Number 602,532 filed January 18, 1911.

15 Having thus described my invention, what I claim and desire to secure by Letters Patent is:—

1. In a glass blowing machine, the combination with a pump, and means for delivering the air displaced by each stroke thereof to a blank, of means for causing a plurality of successive strokes of the pump, each of which is of definite and predetermined length, substantially as described.

20 2. In a glass blowing machine, the combination with a support and a source of air pressure connected therewith, a pump cylinder and a valve for molding air interposed in the connection between the air source and the support, the cylinder having a normally

open connection with the atmosphere, a piston head in the said cylinder, having ports therein, means for actuating the piston head to deliver a charge of air to the support and means for opening the molding valve and closing the connection between the cylinder 35 and the atmosphere.

3. In a glass blowing machine, the combination with a support and a source of air for molding connected therewith, of a pump cylinder interposed in the connection between the blow-pipe and air source, and having a communication with the atmosphere, a valve controlling the said opening, a piston head movable on and with the piston and having ports therein, means for 40 actuating the piston to produce air displacement by the piston head and to close the ports therein, and means for shifting the piston to open the valve between the cylinder and blow-pipe and to close the connection between the cylinder and the atmosphere.

45 In testimony whereof I have signed my name in the presence of two witnesses.
